PROTECTIVE SCREEN

Leon E. Willett, Detroit, Mich., assignor to Chamberlin Company of America, Detroit, Mich., a corporation of Michigan

Application May 4, 1945, Serial No. 591,983

5 Claims. (Cl. 160—391)

1

This invention relates to protective screens, such as are used not only for the purposes and advantages of the ordinary fly or insect screen, but also serve as a personal safeguard. They may be used, for example, on porches or in apartment houses to protect children, in hospitals or other institutions to protect patients temporarily delirious or even the more mild mental cases, or in any other place where substantial protection is desired at relatively low cost.

The invention has for its object to provide a simple screen for the purposes stated, which can be made and sold at relatively low cost, which is capable of manufacture by relatively simple operations, which requires only a few parts, and which yet is strong and not likely to be injured in service and has a pleasing appearance with no suggestion of restraint.

Further objects of the invention in part are obvious and in part will appear more in detail hereinafter.

In the drawings, which represent one suitable embodiment of the invention,

Fig. 1 is an elevation from the inside of the building, parts being broken out and in section;

Fig. 2 is a detail sectional elevation, on a larger scale, on the line 2—2, Fig. 1, the wire panel and certain holding clips being shown somewhat exaggerated, for clearness of illustration; and

Fig. 3 is a sectional plan view on the line 3—3, Fig. 1, and in dotted lines showing the screen panel frame swung out to open position.

The screen shown in the drawings for purposes of illustration is a complete self-contained unit which may be completely fabricated, assembled and finished at the factory and then delivered on the job ready for installation either in a new building during erection, or in a window of an old building. The screen may be applied with either of its faces presented inwardly and either inside or outside of the window sash, depending upon a variety of factors, such as whether the window frames are wood or metal, the sashes slide or swing and if the latter, either inwardly or outwardly, whether window washers will work from the inside or outside, and so on. For convenience, and not in any sense of limitation, it is here assumed that Fig. 1 illustrates that face which is presented to the inside of the building.

The screen includes a strong sturdy frame which may be secured either permanently or removably in the window frame in any desired manner and in which is mounted a screen panel 10 here made of reasonably heavy wire mesh, with openings small enough to keep out insects and

with wire made of any suitable strong material. Stainless steel may be used, but any steel of high tensile strength is satisfactory. The wire should be of gauge or diameter large enough so that it is almost impossible to cut or penetrate it, even with a knife, screw driver or other tools, or by the impact of a heavy object, such as a chair, as is usual in protection or safety screens for this purpose.

10 The frame includes a stationary member 11 and a movable member 12 connected by suitable hinges 13. Both are shown of open rectangular form, although other special shapes may be employed. The two members together, when the screen is in closed position, enclose a cavity 14 which may house any desirable conventional locking mechanism (not shown) capable of actuation to lock or release the swinging frame member by operation of a key inserted into the keyhole 15.

20 Stationary frame member 11 consists of four members (top, bottom and sides) of like cross section mitered and welded together at the corners. This section includes a plain metal body wall 16 bent several times along one edge to form an outer wall 17 a front wall 18 and an inwardly extending edge flange 19. At one, two or more points in the channel thus formed may be welded solid metal blocks 20 to which the hinge leaves may be attached. The other edge of the section is bent inwardly at an angle and then returned upon itself to form a finished bead edge 16a offsetting the screen panel inwardly from this face of the frame, as will be apparent from the drawing.

25 30 35 The movable frame member is likewise made of four like pieces mitered and welded together at the corners. The outer edge of each section is bent laterally to form a cross flange 21, while the inner edge is bent inwardly at an angle to form an inclined wall 22 and then back to form a return flange 23, joined to the inclined wall along a smoothly finished edge 24 spaced slightly from the corresponding finished edge of the stationary frame member to provide a peripheral slot 40 45 through which the screen panel extends.

The return flange 23 serves as the support or mounting means for the screen panel, the four edge portions of which are bent around the edge of said flange and back into parallelism with the panel itself, as shown. Before this bending operation is performed small pieces of the screen panel are cut out at the corners of the sheet to do away with fullness at these points. The actual bending operation is best performed by a 50 55 special bending tool or machine because this

3 heavy wire mesh requires considerably more force to produce the effect than can be applied with the fingers or a simple tool. But when it is accomplished the wire mesh panel becomes almost integral with the flange of the movable frame member, since the interlock between said flange and the U-form edge portion of the screen which embraces it is so strong that ordinary forces such as might be exerted by a child or a hospital patient have no effect. As a matter of fact experience shows that with the particular strong stainless steel wire used for the purpose, the bending operation produces a permanent set in the metal wires so that the effect is much the same as though the wire panel were in fact an imperforate metal sheet permanently interlocked with the mounting flange 23. At least, the usual strains applied to the panel do not straighten out the flange of the panel and pull it loose.

However, if desired, more permanent security may be obtained by applying, over the folded edge of the screen panel, at intervals of say every six inches or so, around the frame, holding clips 24 of U-shape in cross section held in place by small screws or bolts 25, although these are frequently not necessary and may be omitted. When such clips are used, the wire of the wire mesh panel need not be quite so strong or resistant to tension or shock, but in any event always should be heavy and strong enough, and of proper material, to effectively resist penetration by knives or other tools or by the shock of impact of heavy objects.

As shown in Fig. 3, the screen may be unlocked and opened at any time, the movable member swinging out to the position shown in dotted lines. In this position all parts are exposed for cleaning, replacement or repair. When the screen is closed, as in full lines Fig. 3, all panel holding parts are concealed and out of reach of the patient. Also, the inner edges of the holding clips 24 (if they are used), lie just outside of the inclined beaded edge of the stationary frame member which therefore serves as an abutment to assist in preventing the screen panel edge from being pulled out. Indeed, the adjacent body wall 16 of the stationary frame lies so close to the screen panel that of itself it assists in preventing unfolding or opening of the folded panel edge by force applied to the panel.

Other advantages of the invention will be apparent to those skilled in the art.

What I claim is:

1. A protection screen of the character described, comprising a metal frame having a central opening surrounded by screen supporting members, said members providing an inner chamber having a narrow slot opening toward the center of the frame and a flange extending into said chamber from said slot, and a wire screen panel closing the frame opening and at its edges extending into said chamber alongside of said flange and having its edge portions folded around and embracing the edge of said flange, the folded edge of said panel resisting tension applied to the panel and being self-sustaining in its position embracing the frame flange.

2. A protection screen of the character described, comprising a metal frame having a central opening surrounded by screen supporting members, said members providing an inner cham-

ber having a narrow slot opening toward the center of the frame and a flange extending into said chamber from said slot, a wire screen panel closing the frame opening and at its edges extending into said chamber alongside of said flange and having its edge portions folded around and embracing the edge of said flange, the folded edge of said panel resisting tension applied to the panel and is being self-sustaining in its position embracing the frame flange, and U-shaped clips attached at intervals to said flange and embracing it and the fold of wire mesh bent around it.

3. A protection screen of the character described, comprising an open metal frame having stationary and movable members hinged together and relatively movable between open and closed positions, said members each including a body wall and an inner finished edge portion, means spacing the body walls apart when the frame is closed, thereby providing an inner chamber between them, the finished edge of the movable member having a flange lying in a plane parallel to its body wall, and a wire mesh panel covering the frame opening and having its edge portions permanently folded around and embracing the edge of said flange.

4. A protection screen of the character described, comprising an open metal frame having stationary and movable members hinged together and relatively movable between open and closed positions, said members each including a body wall and an inner finished edge portion, means spacing the body walls apart when the frame is closed, thereby providing an inner chamber between them, the finished edge of the movable member having a flange lying in a plane parallel to its body wall, and a wire mesh panel covering the frame opening and having its edge portions permanently folded around and embracing the edge of said flange, said flange and the folded edge of the panel being enclosed within said chamber.

5. A protection screen of the character described, comprising an open metal frame having stationary and movable members hinged together and relatively movable between open and closed positions, said members each including a body wall and an inner finished edge portion, means spacing the body walls apart when the frame is closed, thereby providing an inner chamber between them, the finished edge of the movable member having a flange lying in a plane parallel to its body wall, a wire mesh panel covering the frame opening and having its edge portions permanently folded around and embracing the edge of said flange, said flange and the folded edge of the panel being enclosed within said chamber, and U-shaped clips embracing the folded panel edges and secured to said flange.
